GEORG HEINRICH SCHIEFERSTEIN, OF BERLIN-CHARLOTTENBURG, GERMANY

METHOD OF AND MEANS FOR TRANSFORMING OSCILLATORY MOVEMENT INTO ROTARY MOVEMENT

Application filed January 15, 1929, Serial No. 332,707, and in Germany January 15, 1928.

This invention relates to a method of and mechanism for converting oscillatory into rotary motion.

The invention is based on the discovery that oscillatory units, the amplitude of oscillation of which, when in the loaded condition, varies in accordance with the dimensions of the loading resistance, still completely or approximately completely retain their frequency of oscillation, and that consequently, in combination with rotary systems, such oscillatory systems are in general applicable as automatically variable gears. In the practical working out of such a combination, however, it is also found that an automatically variable gear is not obtained unless the oscillatory energy can be transmitted, together with its characteristic variations in amplitude, to a rotary system; and in all cases this necessitates either a member which partakes in the rotational movement, with a longer or shorter stride, similarly to a free wheel mechanism, or the provision of a member which is adapted to slip in accordance with the resistance.

The first solution entails certain complications and necessitates the employment of unidirectional precision mechanism, while the second, on the other hand, consumes by no means inconsiderable amounts of energy in slipping, thereby generating heat and giving inferior efficiency.

The present invention contemplates a new method for transmitting energy between oscillatory and rotary systems, and mechanism for carrying out this method, which, in accordance with the foregoing, represent the combination of oscillatory and rotary mechanism for automatically modifying the transmission ratio.

The desired effect is obtained by causing a mass which describes circulatory oscillations to compress periodically an annular elastic medium on its periphery, and thus to initiate and maintain a rolling operation whose rotational components can be directly transmitted to rotary members.

In order to more clearly understand the invention, reference is made to the accompanying drawing which illustrates diagram-

matically and by way of example several embodiments thereof.

Figure 1 is a longitudinal section, and

Fig. 1^a an elevation thereof of a typical embodiment of the invention.

Fig. 1^b is a diagrammatic illustration of the operation of the embodiment shown in Fig. 1 with the outer body held fixed.

Fig. 1^c is a diagrammatic illustration of the operation of the embodiment shown in Fig. 1 with the outer body loose.

Fig. 2 is a detail of a type of loose coupling.

Fig. 2^a shows a part of the mass in section with loose coupling, in side view.

Fig. 3 shows a practical embodiment of my device.

Fig. 4 shows how the structures of Fig. 1 may be assembled for balancing.

Fig. 5 is a diagram, and

Fig. 6 is a modification.

Referring to Figs. 1 and 1^a of the drawing, 1 designates the energizing flexible shaft, the terminal portion of which is journaled in the oscillatory mass 2, which is in the form of a hollow body. To this end of the shaft 1 is attached a threaded spindle 3, here shown within the hollow body 2, carrying a weight member 4 that unbalances the shaft and the moment of inertia and force of which is capable of being changed. 5 is an elastic annular body of rubber, which is mounted on a hollow body 6 rotatably supported on a pedestal and surrounds the hollow body 2, and which to some extent resembles a solid or pneumatic rubber tire. This latter body 2 is connected with the shaft 10 by means of a slip coupling comprising two coupling flanges 7 and 9 and a coupling ring 8 lying therebetween in such a manner that it can give way laterally in any direction but actuates the shaft 10 in a positive manner during its rotational movements.

Although couplings fulfilling these conditions are known, an embodiment of such a coupling is illustrated in Figures 2 and 2^a of the accompanying drawing to facilitate the comprehension of the invention.

When the hollow body 6 is in any way hindered in its rotation, for example by brak-

ing it by feather key 18, the mechanism represented in Fig. 1 operates in the following manner:

In rotating, the unbalancing weight member 4 displaces the centre of mass and gravity of the entire hollow body 2 in unison with its speed, that is to say, the elastic medium 5 is compressed (or kneaded) on its periphery by the hollow body, under the action of the 10 unbalancing weight member 4. Since this compression or deformation of the elastic medium 5 occurs, with constant phase displacement, behind the rotating unbalancing weight member, the annular body 2 rolls, as it were, 15 when moved on the annular body 5 and on a larger radius than corresponds to the radius of the hollow body 2 and that of the elastic annular body when at rest. For a flexure f , if the radius of rolling of the hollow, or solid, 20 rubber body 5 be practically R , and that of the oscillatory hollow body 2 be r , there must result, for each revolution of the unbalanced weight member 4 a difference of $x = R\pi - r\pi$ in the path traversed by said body, hence the 25 hollow body 2 must lag, by this difference, behind the annular body 6 at each revolution of the unbalancing weight member.

The transmission ratio in each case thus works out as

$$30 \quad \frac{f}{r}$$

However, since f is a variable amplitude, which alters with the resistance, the transmission ratio naturally also varies to the same degree. The mass 2 describes oscillations, inside the annular elastic body 5, which in practice deforms the resilient rings 5, and in effect increases the interior radius of the annular body 5 and therefore produces a rolling effect of the body 2 on the rings 5. The degree of flexure of the annular body 5, or the amplitude f , depends on the damping sustained by the whole arrangement, or on the 40 resistance which the entire arrangement has to overcome. If this resistance continually varies, the amplitude of oscillation and the flexure f vary accordingly, and the transmission ratio varies in the same proportion. The 45 mechanism thus acts as a self-adjusting, continuously variable transmission gear.

If the annular body 6 and the resilient means 5 are held fixed against rotation while the mass 2 oscillates circularly and is loose on its shaft, the elastic means will be periodically compressed at its periphery, that is, during the compression a normal force N is transmitted by the elastic means on the oscillating mass 2 or an axial pressure is exerted 60 on the shaft.

This normal force produces a frictional force which is perpendicular to the normal force and has the magnitude $R = \mu N$, where μ is the coefficient of friction.

65 The frictional force always effects move-

ment of the member producing the normal force, that is, in this case against the circularly swinging mass 2, or of the member acted upon by the normal force which produces the frictional force, the frictional force therefore produces a rotary movement of mass 2 in the direction of the frictional force R and opposite the direction of the circular oscillation and, with it, in the rotational direction of the unbalanced member 4.

If on the contrary, the inner mass 2 is held fixed and the outer annular member 6 with the elastic means 5 are journaled loosely on the shaft, the reaction of the frictional force R or the peripheral force of the fixed mass acts on the outer wheel, that is, this moves in the direction of the circular oscillation and in the direction of the rotary movement of the unbalanced member 4.

Thus, for example, as a practical application of the present invention, each of the two driving wheels of a vehicle can be fitted up substantially as represented diagrammatically in Figure 3. In the rotation of the two unbalanced weight members 4, which are offset at 180° , the two hollow bodies 2 (which are prevented from rotation by corresponding clutch mechanism) describe circular oscillations which produce a rolling effect actuating the two wheel rims 6. Since the peripheral velocity of each wheel rim adjusts itself in accordance with the resistance present for the time being, the device also acts at the same time as a differential gear, in travelling around curves, in which case, as is well known, the two wheels encounter different resistances.

Fundamentally, it is immaterial whether the elastic annular body 5 is secured to the rigid annular body 6, so that the body 2 describes a combined oscillatory and rolling movement, or whether the annular body 5 is secured to the hollow body 2, and the rolling movement takes place between the elastic body 5 and the rigid body 6. In the latter case, however, the stressing of the elastic medium is generally less favorable than in the former. The annular body 5 may, of course, also be designed as a hollow body, and may for example, be similar to a pneumatic tire.

Fig. 4 represents four of the sets of mechanism shown in Fig. 1 coupled together in such a way that the influence of the oscillatory systems as well as the influence of the unbalanced members balance each other. The unbalanced members, two of which are disposed in the same direction, and two offset by 180° in relation thereto, naturally set up, within the oscillatory units and with the same displacement, oscillations that counteract each other externally in respect of force and inertia action, without affecting in detail the oscillatory operation or the rolling or rotational operation.

Drives of the type illustrated in Fig. 4

are particularly suitable for vehicles and machines which must not be subjected to vibration, but in which the transmission ratio must adjust itself automatically in accordance with the resistance, for example, in the case of motor lorries, pit locomotives, lifting machines, planing machines, lathes and the like.

If a tractor of the type illustrated in Fig. 10 3 be provided with two sets of gear which are not balanced with respect of the action of force and inertia, the periodical action of force or inertia is utilized, in this case, in order to increase the reaction of the tractor 15 to the ground periodically. The reaction of a tractor with uniform power drive is based solely on the adhesion, due to the weight of the tractor, between the driving wheels and the ground. If the adhesion be increased, as 20 in the present instance, by the periodical action of force, the tractive power of the tractor is increased.

In Fig. 5, this operation is illustrated by a curve. The tractive force of a uniform 25 power tractor is expressed by the ordinates y . Since this tractive power is steadily and continuously exerted, when the uniform-power principle is applied, the work performed in the time x is represented by 30 $A = x \cdot y$. If, in applying the variable power principle in the sense of the present invention, the maximum force of reaction is increased to $y_1 = 2y$, by the periodical action of force, say in accordance with the sine law, 35 a working curve is obtained which approximately follows the course of the curve OA, B, C, D, E . . . . . and so on. The working diagram comprised by this curve corresponds in its details to the working diagram x, y since 40 the section ABC can be brought into the position CDE by rotation through 180° . The work performed therefore remains the same, whereas the force of reaction, and accordingly the adhesion between wheel and track has 45 risen to double. Since the tractive power of a tractor depends solely on the maximum force, and not on the work, the tractive power is increased to a corresponding extent.

The coupling shown in Fig. 2 consists of 50 the two discs 7 and 9, and an intermediate square plate 8, indicated by broken lines.

Four rollers 14 fast on the coupling disc 7 engage the intermediate plate 8 on opposite parallel sides and permit it to describe movements in one direction in relation to the disc 55 7. Four rollers 15 mounted on the disc 9 engage the other two parallel sides of the intermediate plate 8 and permit a relative movement between 8 and 9 in a direction at an angle of 90° in relation to the first movement. In effect therefore, the coupling enables relative displacement to occur between 60 7 and 9 in any desired radial direction, while preventing any rotational movement between 65 7 and 9.

The embodiments hereinbefore described, and illustrated in the drawing, are given merely by way of example, since it is possible to produce the most divergent combinations by changing the elastic medium and masses. 70 Moreover, the principle of converting oscillatory into rotary movement underlying the invention, is not intended to be restricted to any specific details, and particularly to the intentional employment of coupling members 75 of fixed dimensions in place of the variable loose coupling.

If it be desired to convert oscillatory into rotational movements without thereby obtaining an automatic variation in the ratio of 80 transmission, then, as illustrated in Fig. 6, the oscillating body 2, describing circular oscillations of constant amplitude, can be so designed as to allow it to rotate, for example, on a crank 17. All the other effects then adjust themselves accordingly, in the manner hereinbefore described.

I claim—

1. Mechanism for transforming oscillatory into rotary movement, which comprises 90 a mass and elastic means on which the mass rolls and is deformed thereby, a driving shaft connected to the mass, a driven shaft for said means and a yielding connecting means between said means and driven shaft. 95

2. Mechanism for automatically varying the speed ratio in an oscillatory system, comprising a mass and an elastic member cooperating therewith and upon which the mass rolls, means to excite the system to oscillation and thereby cause a rolling of the mass, means to damp the rolling of the mass by causing a variation of the rolling radius, a driven rotary member, and means to transmit the resultant-rotary components of the system to the driven member. 105

3. Mechanism for transforming mechanical forces and speeds, which comprises power transmitting means, means to transmit the power of said transmitting means into oscillatory form of relatively small force and relatively high speed in automatically varying ratios, and means to transmit said oscillatory power into oscillatory power of relatively high force and relatively low speed, and means to transform the latter oscillatory power into rotary forces. 110

4. Mechanism for transforming mechanical forces and speeds, which comprises rotary power transmitting means, oscillatory means to translate said power into oscillatory power having a relatively high speed component and small force component, and means to translate said oscillatory power into small speed 120 component and high force component.

5. Mechanism for transforming mechanical forces and speeds, which comprises driving means, means having opposed masses to produce oscillating forces whose maximum is 130

vertical, and means to translate said oscillatory forces into rotary forces.

6. A mechanism comprising driving means, a plurality of gyrators driven thereby, means to which said gyrators transmit their motion, elastic means with which said latter means co-act to produce a circular rolling movement thereof, means for displacing the phases of gyration, and means to translate the gyratory movement into circular movement.

7. In a device for transforming gyrating motion into rotary motion, comprising a mass, means to gyrate said mass, a ring-shaped elastic means cooperating with the mass and deformed by the gyrations of the mass whose radius of rotation is varied and controlled by said elastic means, a rotary driven member and means to transmit rotary movement from the gyrating mass to said member.

8. In a device for transforming rotary oscillations into rotary movement, a gyrating member, a mass to gyrate said member, ring-shaped elastic means surrounding said member and mass, said member de-forming said elastic means during its gyrations and thereby caused to roll, a driven rotary device and means to yieldingly connect the member and device.

9. In a device for transforming oscillating movement into rotary movement; a driven gyratory weight, a member containing said weight, a second member surrounding the first member, elastic means between the two members surrounding the first member and deformed by the rolling of the first member on the elastic means, said rolling caused by the gyrations of said weight, a driven shaft and a connection between the first member and shaft permitting excentric movement of said first member with respect to said shaft.

10. In a device for transforming rotary oscillatory movement into rotary movement; a driven gyratory weight, a rotary member containing said weight and oscillated thereby, a second member spaced from and surrounding the first member, elastic means secured to one of the members, surrounding the first member in the space between the members, a driven shaft and coupling between the shaft and first member permitting excentric movement of the first member while transmitting rotary movement of the shaft.

11. In a device for transforming rotary oscillating movement into rotary movement, a driving shaft, a weight adjustable excentrically thereto, a hollow mass in which said shaft and weight are mounted, a member spaced from and surrounding the mass, a rubber ring secured to the member and engaging the mass and on which the latter rolls, a driven shaft and a clutch between the mass and shaft permitting excentric movement of the mass with respect to the shaft.

12. In a device for transforming rotary oscillatory movement into rotation, a driven sectional shaft the sections of which are loosely coupled together, an adjustable weight excentric to each section, an oscillating mass on each section surrounding the weight thereon, a loose coupling between the masses, a member surrounding each mass, elastic rings between the member and masses, the weights of the respective members being angularly displaced to produce gyrations displaced in phase, a rotary driven member and a loose coupling between the last mass and driven member to drive the latter while permitting excentric movements of the latter.

In testimony whereof I affix my signature.
